UNITED STATES PATENT OFFICE.

JEFFERSON FULLER, OF HUNTINGTON, WEST VIRGINIA.

CAR-COUPING.

SPECIFICATION forming part of Letters Patent No. 315,401, dated April 7, 1885.

Application filed October 9, 1884. (No model.)

To all whom it may concern:

Be it known that I, JEFFERSON FULLER, a citizen of the United States, residing at Huntington, in the county of Cabell and State of 5 West Virginia, have invented certain new and useful Improvements in Car-Couplings, of which the following is a description.

This invention relates to that class of devices which are intended to couple cars automatically, and it has for its object to arrange the link-pin to fall in place at the right time without the use of springs, and to manage the pin from either side or from the top of the cars.

15 To this end my invention consists in the construction and combination of parts forming a car-coupling, hereinafter described and claimed, reference being had to the accompanying drawings, in which—

20 Figure 1 is an end elevation of a car, showing my invention; and Fig. 2 is a longitudinal vertical section of the coupling on a larger scale.

A represents a freight-car.

25 B is the draw-head attached in any usual manner to the car. The mouth of the draw-head is flaring or hopper-shaped to direct the approaching link into it. The lower side, C, of the throat is concave or trough-shaped to assist in guiding the link into a central position.

30 D is the link-pin, which may be of the usual cylindrical form, and be slotted to receive a fixed pin to prevent its removal from the draw-head; but I prefer to make the pin rounded on one side and flat on the other and cut away at one corner, E, except at the lower end, and I use in connection with this cornered pin a stop pin or screw, F, to engage the remaining corner below the cut-away E to prevent the removal of the pin, yet permitting the pin to rise and fall in its hole enough to admit and hold the link G.

35 H is a perforated latch through which the pin D passes on its way downward. This latch is pivoted at its lower forward corner, I, and it is so thick that while the lower face of the latch rises the upper face in the region

of the pin-hole moves forward. When the latch falls of its own weight into its normal 50 position in the path of the link, as shown in Fig. 2, the pin is supported on its upper side close in front of the pin-hole. When a link enters the draw-head, it pushes the latch up out of its way, thereby bringing the pin-hole 55 in the latch under the pin, and allowing the pin to drop through the latch and through the link, thus holding the link.

K is a lever loosely hung in long loops L, which are attached to the sides of the car. 60 The lever is provided with shoulders M to prevent its removal from the loops L.

N is a cord connecting the link-pin with the center of the lever K. The lever, extending to the sides of the car, enables a person to raise 65 the pin without going between the cars. The cord O extends from the pin to the top of the car, to enable a person there to draw the pin.

When the forward car is slackened a little, the rear car will approach enough by its momentum so that the cars may be disengaged while in motion, if so desired, by any person on top of the cars. When the link is withdrawn, the latch drops and will hold the pin ready to engage the next incoming link. The 75 latch is so thick that if it is down its pin-hole is too much out of line with the pin-hole in the top and bottom of the draw-head to permit a pin to be forced through it.

What I claim as my invention, and desire to 80 secure by Letters Patent, is—

The combination, with a draw-head, a link-pin, and means for supporting it in the draw-head when raised, of a lever extending across the end of the car, two rods, L, attached to 85 the car forming loops to hold the ends of the lever loosely, shoulders upon the lever increasing its thickness to bear endwise against the said rods or loops, and a rope or chain connecting the middle of the lever with the 90 link-pin, substantially as shown and described.

JEFFERSON FULLER.
